METHOD OF PREPARING PETROLEUM FRACTION OF IMPROVED ODOR USING β -LACTONES

TONES
George W. Ayers, Chicago, and William A. Krewer,
Arlington Heights, Ill., assignors to The Pure Oil Com-
pany, Chicago, Ill., a corporation of Ohio
No Drawing. Filed May 3, 1961, Ser. No. 120,456
20 Claims. (Cl. 208—199)

This invention relates to the preparation of petroleum fractions of improved odor and, more particularly, to the use of β -lactones in improving the odor of distillate furnace oils.

The presence of appreciable quantities of mercaptans in distillate furnace oils, or components thereof, obtained from many crude oils, is undesirable due to their very objectionable odors. The odors of such petroleum fractions must be improved before they are suitable for marketing. The odors are improved either by removing the mercaptans from the oils or by converting them into substances having lower odor-imparting characteristics. One of the well-known processes for converting these objectional substances to less obnoxious compounds is "doctor treatment." In this sweetening process, the odorous petroleum fraction is treated with an aqueous solution of an alkali metal hydroxide containing sodium plumbite and elementary sulfur. The mercaptans are converted into disulfides, which have much lower odor-imparting properties, and the doctor-treated petroleum fraction exhibits a great improvement in odor. The amount of elementary sulfur used in doctor treatment is rigidly controlled so that barely enough sulfur is present to obtain precipitation, or "break," of lead sulfide from the petroleum fraction and conversion of mercaptans into disulfides. The settling of the dark-colored material from the petroleum fractions leaves a clear "sweetened" product of good odor. The principal disadvantages of the doctor treatment are that the sulfur content of the product oil is essentially the same as that of the untreated oil, and that extreme care must be exercised not to use excess sulfur or the product oil will be corrosive to metals such as copper and hence unsuitable for marketing. In addition, in the case of certain very odorous petroleum fractions, extreme difficulty is experienced in obtaining the "break" even when an undesirable excess of sulfur is present, and a long time interval may be required.

In accordance with the present invention, it has been found that the odor of furnace oils is improved by treatment with a β -lactone and an alkali metal hydroxide. It has been found that in treating odiferous furnace oils with an aqueous alkali metal hydroxide solution and a β -lactone, a portion of the obnoxious sulfur compounds which imparts odors to the oils is removed and there is a decrease in the total sulfur content of the treated oils. It has also been found that a preliminary treatment of exceedingly odiferous petroleum fractions with a β -lactone and an aqueous alkali metal hydroxide solution significantly reduces the time required for the doctor "break," as well as the sulfur requirement, during a subsequent doctor treatment. As an alternative method of application, the β -lactone may be added to the doctor solution. Other methods of application will become apparent from a further description of this invention.

Accordingly, it is a primary object of this invention to provide a process of preparing a petroleum fraction of improved odor.

Another object of this invention is to provide a process for sweetening furnace oils.

Another object of this invention is to provide a reduction in the time and elementary sulfur requirements for doctor-treating petroleum fractions.

2

Another object of this invention is to provide a process for removing odoriferous materials from petroleum fractions by treatment with an aqueous alkali metal hydroxide solution and a β -lactone.

- 5 These and further objects of the invention will become apparent as the specification herein proceeds.

This invention is directed to the use of the combination of a β -lactone and caustic solution in removing odoriferous substances from certain petroleum fractions.

10 The β -lactones which are used have the reactive nucleus

- 15 with the free valences preferably satisfied by hydrogen or hydrocarbon radicals such as alkyl, cycloalkyl, aryl or alkaryl radicals. More specifically, it is preferred that the hydrocarbon radicals contain 1 to 10 carbon atoms. Non-limiting examples of compounds coming
20 within the scope of the foregoing formula and definition are:

β -Propiolactone
 β -Butyrolactone (β -methyl- β -propiolactone)
 β -Methyl- β -butyrolactone (β - β -dimethyl- β -propiolactone)
25 β -Ethyl- β -butyrolactone
 β -Phenyl- β -propiolactone

The β -lactone reacts especially with tertiary mercaptans, such as aromatic mercaptans of the thiophenol type, in the presence of the alkali solution. The mercaptans are converted into water-soluble substances, thus lowering the sulfur content of the petroleum fraction. The reaction proceeds as represented by the following equation:

- 45 The β -lactones show a negligible reactivity with the mercaptans unless a caustic solution is present. The β -lactone and caustic may be added to the petroleum fraction simultaneously or separately. It is preferred that the β -lactone not be added to the caustic solution prior to the caustic solution being added to the petroleum fraction.

50 since the lactone will also react with it to give, with β -propiolactone for example, sodium hydracrylate. This reaction is less rapid than the reaction with the mercaptans. If the β -propiolactone is added to the caustic solution for any appreciable length of time prior to its use

55 in treating the sour petroleum fraction, appreciable amounts of the β -lactone will be lost in the reaction with the caustic solution.

The amount of the β -lactone used per amount of petroleum fraction will depend upon the amount of the reactive odoriferous mercaptans present in the petroleum fraction to be treated. At least a stoichiometric amount of the β -lactone to react with the active mercaptans present in the petroleum fraction should be used. An excess over the stoichiometric amount is recommended.

65 A temperature of about 150° to 230° F. is preferred during the treatment of the oil with the β -lactone and aqueous caustic solution. Other temperatures may be used, but temperatures lower than about 150° F. will require longer contact periods than are considered practical. A contact time of about one to ten minutes is effective at temperatures of about 150° to 230° F. The method of contacting may be mechanical or by turbulent

70

flow. The process of this invention may be conducted batchwise as well as continuously.

At least a stoichiometric amount of the caustic soda is added preferably as a 1 to 25% aqueous solution, although other concentrations may be used. Although sodium hydroxide is preferred because of its cheapness, other alkali metal hydroxides, such as potassium hydroxide or lithium hydroxide, or any combination of these three alkali metal hydroxides, may be used. The caustic solution may be used repeatedly, (1) with periodic additions of fresh caustic, until the accumulation of salts necessitates discarding the solution, or (2) with continuous or periodic additions of fresh caustic (or caustic solution) with continuous or periodic withdrawals of equivalent volumes of the used caustic solution.

If the β -lactone is added during the doctor treatment instead of being used in a preliminary treatment with an aqueous alkali metal hydroxide solution, not more than one mole of β -lactone should be used per mole of mercaptan present in the oil to be treated. This is preferred to prevent rapid fouling of the doctor solution with alkali metal salts which are not removed by the usual methods of regeneration of the doctor solution.

The petroleum fractions that can be treated successfully in accordance with this invention include those that contain tertiary mercaptans, particularly aromatic mercaptans of thiophenolic type and other mercaptans not of the primary or secondary types, as an appreciable part of their mercaptan content. Virgin and cracked petroleum fractions boiling in the range of approximately 300° F. to 700° F. are especially susceptible to treatment in accordance with this invention. The present invention is also specially applicable to those petroleum fractions with which difficulty is experienced in obtaining breakout of doctor sludge during doctor treating.

In order to demonstrate the invention, the following examples are presented:

Example I

A 100-gram sample of a poor-odor-quality furnace-oil stock (352-550° F. boiling range), obtained from a mixture of western sour crude oils and containing 0.05% mercaptan sulfur and 0.53% total sulfur, was treated with 10 grams of 20% sodium hydroxide solution and 3.6 grams of β -propiolactone at 230° F. for one hour with mechanical stirring. After this treatment, the mixture was cooled to room temperature and the oil and aqueous phases were separated. Following this, the oil was water-washed until the washings were no longer basic. The washed product was found to show a great improvement in odor quality and was very suitable for marketing.

Another portion of the furnace oil was treated in a like manner except that the contacting was done at room temperature. The odor of the product was inferior to that of the product of the first treatment, but was suitable for marketing.

Another 100 grams of poor-odor-quality furnace-oil stock was treated under similar conditions except the β -propiolactone was omitted. This treatment had little or no effect on the odor quality of the furnace-oil stock.

A similar treatment of 100 grams of the furnace-oil stock was conducted except the sodium hydroxide was omitted. This treatment was without effect on the odor quality and the product remained unmarketable.

Example II

A 100-gram sample of cycle stock (442-625° F. boiling range), having a very obnoxious odor and containing 0.007% mercaptan sulfur and 1.01% total sulfur, was treated with two grams of 20% sodium hydroxide solution and 0.7 gram of β -propiolactone at 230° F. for 15 minutes with mechanical stirring. The oil and aqueous phases were then separated after the mixture had cooled to room temperature. The oil was water-washed to re-

move any remaining alkali. The treated oil had a greatly improved odor and was marketable.

Example III

One hundred grams of untreated furnace oil (boiling range similar to that of the furnace oil used in Example I), containing 0.93% total sulfur and 0.046% mercaptan sulfur, and of very poor odor quality, was treated with 10 grams of 20% sodium hydroxide solution and 3.6 grams of β -propiolactone at 230° F. for five minutes with mechanical stirring. After the mixture had cooled to room temperature, the oil phase was separated and water-washed to neutrality. The odor of the oil was significantly improved, but the oil was not doctor-sweet. The oil was then treated with an excess of doctor solution, and 0.014 gram of sulfur, an amount just sufficient to obtain a break of the doctor sludge. The break was complete within about two minutes. The odor of the doctor-sweet treated oil was very satisfactory and the product was suitable for marketing.

Another 100-gram sample of the furnace oil was agitated with a large excess of doctor solution while 3.6 grams of β -propiolactone were added slowly. After about three minutes, sulfur was added in small increments until a break was obtained. Sixteen-thousandths of one gram of sulfur was added to obtain a break in about two minutes. The product separated was doctor-sweet, of greatly improved odor, and marketable.

A third 100-gram sample of the furnace oil was treated with an excess of doctor solution and with elementary sulfur after a preliminary treatment with 20 grams of 20% sodium hydroxide solution for one hour at 230° F. In the doctor treatment, 0.025 gram of sulfur was required to obtain a break which was not complete until after about two hours. The odor of the doctor-sweet product was satisfactory and it was marketable.

Example IV

One hundred grams of very sour, poor-odor-quality, untreated V.M. & P. naphtha (236-289° F. boiling range), containing alkyl mercaptans mainly of primary and/or secondary types, was treated with 3.6 grams of β -propiolactone and 10 grams of 20% sodium hydroxide solution under the conditions described in Example I. The odor of the product was unpleasant, rendering it unmarketable as a naphtha. Another portion of the untreated V.M. & P. naphtha was subjected to similar treatment except that β -propiolactone was added slowly over a 45-minute period. The odor quality of the naphtha was not improved by this treatment.

This example demonstrates that the process of this invention is not effective in improving the odor of certain petroleum fractions. The sour V.M. & P. naphtha, which contained mercaptans mainly of primary and secondary types, was not noticeably improved in odor when it was treated in accordance with this invention.

The embodiments of the invention in which an exclusive property or privilege is claimed are defined as follows:

1. A method of preparing a petroleum fraction of improved odor, which comprises treating a mercaptan-containing petroleum fraction with a reagent consisting essentially of a β -lactone and an aqueous solution containing an alkali metal hydroxide.
2. A method in accordance with claim 1 wherein said β -lactone has the reactive nucleus:

70 with the free valences satisfied by the same or different substituent radicals selected from the group consisting of hydrogen and hydrocarbon radicals containing 1 to 10 carbon atoms.

75 3. A method in accordance with claim 2 wherein said β -lactone is β -propiolactone.

4. A method in accordance with claim 1 wherein said alkali metal hydroxide is present in said aqueous solution in an amount included in the range of about 1 to 25% by weight.

5. A method in accordance with claim 1 wherein the treatment is conducted at a temperature of at least 150° F.

6. A method in accordance with claim 1 wherein said petroleum fraction boils within the range of approximately 300° F. to 700° F. and contains tertiary mercaptans as an appreciable proportion of its mercaptan content.

7. A method in accordance with claim 6 wherein said tertiary mercaptans are aromatic mercaptans of the thiophenol type.

8. In a method of preparing a doctor-sweet petroleum fraction of improved odor wherein a mercaptan-containing petroleum fraction is treated with doctor solution and elementary sulfur, the improvement comprising preliminarily treating said petroleum fraction with a reagent consisting essentially of a β -lactone and an aqueous solution containing an alkali metal hydroxide.

9. A method in accordance with claim 8 wherein said β -lactone has the reactive nucleus:

with the free valences satisfied by the same or different substituent radicals selected from the group consisting of hydrogen and hydrocarbon radicals containing 1 to 10 carbon atoms.

10. A method in accordance with claim 9 wherein said β -lactone is β -propiolactone.

11. A method in accordance with claim 8 wherein said alkali metal hydroxide is present in said aqueous solution in an amount included in the range of about 1 to 25% by weight.

12. A method in accordance with claim 8 wherein said preliminary treatment is conducted at a temperature of at least 150° F.

13. A method in accordance with claim 8 wherein said petroleum fraction boils within the range of approximately 300° F. to 700° F. and contains tertiary mercaptans as an appreciable proportion of its mercaptan content.

14. A method in accordance with claim 13 wherein said tertiary mercaptans are aromatic mercaptans of the thiophenol type.

15. In a method of preparing a doctor-sweet petroleum fraction of improved odor wherein a mercaptan-containing petroleum fraction is treated with a doctor solution and elementary sulfur, the improvement comprising adding to said doctor solution a reagent consisting essentially of a β -lactone.

16. A method in accordance with claim 15 wherein said β -lactone has the reactive nucleus:

with the free valences satisfied by the same or different substituent radicals selected from the group consisting of hydrogen and hydrocarbon radicals containing 1 to 10 carbon atoms.

17. A method of preparing a petroleum fraction of

improved odor, which comprises treating a mercaptan-containing petroleum fraction containing tertiary mercaptans as an appreciable proportion of its mercaptan content with a reagent consisting essentially of a β -lactone having the reactive nucleus:

10 with the free valences satisfied by the same or different substituent radicals selected from the group consisting of hydrogen and hydrocarbon radicals containing 1 to 10 carbon atoms, in the presence of an aqueous solution containing from about 1 to 25% by weight of an alkali metal hydroxide, said β -lactone and alkali metal hydroxide being used in amount at least equivalent to the tertiary mercaptan content of said petroleum fraction, for a period of time sufficient to produce a petroleum fraction of improved odor.

15 18. In a method of preparing a doctor-sweet petroleum fraction of improved odor wherein a mercaptan-containing petroleum fraction containing tertiary mercaptans as an appreciable proportion of its mercaptan content is treated with doctor solution and elementary sulfur, the improvement comprising preliminary treating said petroleum fraction with a reagent consisting essentially of a β -lactone having the reactive nucleus:

30 with the free valences satisfied by the same or different substituent radicals selected from the group consisting of hydrogen and hydrocarbon radicals containing 1 to 10 carbon atoms, in the presence of an aqueous solution containing from about 1 to 25% by weight of an alkali metal hydroxide, said β -lactone and alkali metal hydroxide being used in amounts at least equivalent to the tertiary mercaptan content of said petroleum fraction, for a period of time sufficient to produce a petroleum fraction of improved odor.

35 19. In a method of preparing a doctor-sweet petroleum fraction of improved odor wherein a mercaptan-containing petroleum fraction containing tertiary mercaptans as an appreciable proportion of its mercaptan content is treated with a doctor solution and elementary sulfur, the improvement comprising adding to said doctor solution a β -lactone having the reactive nucleus:

40 with the free valences satisfied by the same or different substituent radicals selected from the group consisting of hydrogen and hydrocarbon radicals containing 1 to 10 carbon atoms, said β -lactone being used in an amount such that the mole ratio of β -lactone to mercaptans is not greater than 1:1.

45 50 55 20. A method in accordance with claim 16 wherein said β -lactone is β -propiolactone.
